UNITED STATES PATENT OFFICE.

JOHN J. PIERRE, OF FREEPORT, NEW YORK.

ERASER ATTACHMENT FOR TYPE-WRITERS.

1,185,533.

Specification of Letters Patent.

Patented May 30, 1916.

Application filed February 12, 1916. Serial No. 77,955.

To all whom it may concern:

Be it known that I, JOHN J. PIERRE, a citizen of the United States, residing at Freeport, Long Island, in the county of Nassau and State of New York, have invented certain new and useful Improvements in Eraser Attachments for Type-Writers; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to certain new and useful improvements in attachments for typewriting machines and it has for its specific object the provision of an attachment for use in correcting errors in writing without the necessity of removing the paper from the line of writing and also obviates the necessity of using erasers now commonly employed for this purpose, thereby effecting a large saving of time incident to the looking for an eraser when an error has been made in typewriting.

To these ends and to such others as the invention may pertain, the same consists in the novel construction and in the peculiar arrangement, combination and adaptation of parts, all as will be more fully hereinafter described, shown in the accompanying drawings and then specifically defined in the appended claims.

The invention is illustrated in the accompanying drawings which, with the numerals of reference marked thereon, form a part of this specification and in which:—

Figure 1 is a top plan view of a visible typewriter showing my invention applied thereto. Fig. 2 is a view on line 2—2 of Fig. 1. Fig. 3 is a detail in side elevation of the eraser block carrier. Fig. 4 is a like view of the eraser block removed, and Fig. 5 is a top plan view of a portion of a sheet of paper showing the relative position of the eraser block when in use.

Reference now being had to the details of the drawings by numeral, 1, 1 represent the opposite sides of the top of a typewriter frame, and 2 the platen of the machine.

3 is a metallic strip, the ends of which are bent downward and held to the face of the typewriter frame by screws or other fastening means, as shown at 4.

5 is a shaft, the body portion of which is provided upon its upper side with a rack bar 14, the teeth of which rack engage the teeth provided upon the face of an enlarged portion 15 of a shaft 16, one end of which shaft extends beyond the front of the typewriter and is provided at its extended end with a push button 17 by means of which the shaft may be forced inward, its return to its normal position or extreme outward throw being automatically accomplished by a spring 18. The inner end of the shaft 16 is provided with a suitable holder 19 to receive an eraser block 20, the preferable form of which is shown in the drawings as a truncated pyramid, the face portion of which is received within the holder 19. The shaft 5 is suitably journaled in the bracket 8 and the downwardly depending arm 6 of the member 3. 21 is a spring around the inner end of this shaft 5, bearing at one end against the bracket 8, the other end of said shaft being extended beyond the outer edge of the typewriter frame and has fixed thereon a collar 9.

10 is a bell crank lever journaled within suitable bearings provided in the bracket 11 upon the outer end of the typewriter frame. One arm of the bell crank lever has pivoted thereto one end of a link 12, the other end of which is connected to a member 22 mounted loosely on the rod 5 and adapted to abut against the collar 9. The other member or arm 23 of the bell crank lever is suitably connected with an operating key 24, as shown. Upon the opposite end of the typewriter frame, I have shown in dotted lines a shaft 25, the outer end of which is extended beyond the end of the frame and provided with an operating lever 26, which may be connected to a key on the key board, the movement of which lever will, through the mechanism of the crank arm 27 at its inner end with a movable collar 26 upon the shaft 16, serve to impart an upward movement to said shaft, thereby forcing the eraser block into contact with the paper upon the platen of the machine at the point at which the letter is to be erased, the shaft being rotated by the engagement of the teeth upon the rack bar with the serrations or teeth upon the body portion 15 opposite said shaft 6.

As it will be at once evident that the center of the eraser block will not have an abrading effect or movement and it is necessary to utilize the outer portion of the

block only, the central point of the block is positioned a short distance below the center of the letter to be erased as indicated at the point 27 in Fig. 5.

5 From the foregoing description, the operation of the device will be at once readily understood. When it is designed to throw the eraser block into operative position relative to the platen, this is accomplished by 10 forcing the shaft 16 inward against the action of the spring 18. This inward thrust will cause the erasing surface of the eraser block to be thrown into contact with the paper at the point at which the letter to be 15 erased is located. By forcing downward the arm of the bell crank lever to its engagement with the operating rod 23, the shaft will, through the means of the pivoted bell crank lever, be forced inward, thus rotating 20 the eraser carrying shaft 16 and, upon releasing the pressure upon the key 24, the eraser block will be rotated in an opposite direction by the action of the spring 21.

It will be noted that the longitudinal 25 movement imparted to the shaft 16 carrying the eraser block may be accomplished either by an inward pressure applied to the button or handle upon the outer end of the shaft or by means of the lever 26.

30 Having thus described my invention, what I claim to be new and desire to secure by Letters Patent is:

1. An erasing attachment for typewriters, embodying a supporting member, a shaft 35 supported therein, an erasing block disposed for end engagement with the paper on the platen, and means for rotating the block from said shaft said block being so disposed that the outer portion only of the end 40 surface of the block is utilized for erasing purposes.

2. An erasing attachment for typewriters, embodying a supporting member, a shaft supported therein, a tapered erasing block 45 disposed for end engagement with the paper on the platen, means for rotating the block from said shaft said block being so disposed that the outer portion only of the end surface of the block is utilized for erasing 50 purposes, and means for reversing the direction of rotation of said block to withdraw it from engagement with the paper.

3. An erasing attachment for typewriters comprising a supporting member for attachment to a typewriter frame, a shaft longitudinally movable in bearings on said member, a transversely disposed rotatable shaft mounted in said member, a polygonal

erasing block carried by the last-named shaft, and interengaging means on the two 60 shafts for causing the rotation of the last-named shaft by the reciprocation of the former.

4. An erasing attachment for typewriters comprising a supporting member for attachment to a typewriter frame, a shaft longitudinally movable in bearings on said member, a transversely disposed rotatable shaft mounted in said member, a polygonal erasing block carried by the last-named 70 shaft, interengaging means on the two shafts for causing the rotation of the last-named shaft by the reciprocation of the former, a spring for returning the first-named shaft to its normal position, and a 75 spring acting on the second-named shaft to return it to its normal position.

5. In an eraser attachment for typewriters, an eraser block holder movable longitudinally to present the face of an eraser 80 block into contact with the platen of a typewriter, the shaft of the eraser holder being provided with an elongated body portion, serrated as described, a reciprocatory transverse shaft provided with a rack bar 85 so positioned as to engage the teeth or serrations upon the shaft of the eraser block holder to effect a rotation thereof, substantially as shown and described.

6. In a device of the character described, 90 the combination with a typewriting frame, of an eraser block holder and an eraser block of polygonal form carried thereby for end engagement with the paper, means whereby the shaft of the eraser holder can 95 be rotated in one direction by the depression of an operating lever and in its opposite direction automatically rotated by spring action, substantially as shown and described.

7. In a device of the character described, 100 the combination with a typewriter of a movable eraser holder adapted to be moved inward to position an eraser block of polygonal form in end contact with the platen of a typewriter, means for rotating the 105 eraser block holder; and means for automatically retracting and withdrawing the eraser block from its operative position, substantially as shown and described.

In testimony whereof I hereunto affix my 110 signature in presence of two witnesses.

JOHN J. PIERRE.
